UNITED STATES PATENT OFFICE.

JOHN RANK AND HENRY W. RANK, OF MINNEAPOLIS, MINNESOTA.

ANCHORING BASE FOR TRAFFIC SIGNALS.

Application filed October 21, 1925. Serial No. 63,995.

Our invention relates to traffic signals of the type wherein a yielding self-aligning signal post is placed in the street, and the invention is directed to an improved anchoring base adapted to be located in the pavement or roadway, and to which the base is adapted to be anchored.

The improved anchoring base is especially designed and particularly adapted for use in connection with traffic signals of the character disclosed and claimed in our prior application filed September 3, 1925, under Serial Number 54,240, and entitled "Traffic signals."

15 In the accompanying drawings, which illustrate the invention, like characters indicate like parts throughout the several views.

Referring to the drawings:

Fig. 1 is a view in elevation showing the anchoring base applied to support a signal post from concrete pavement, the latter being shown in section; and

20 Fig. 2 is an enlarged fragmentary view partly in section and partly in elevation showing the base on a larger scale than in Fig. 1.

The concrete pavement is indicated by the character y . The base comprises an upright anchoring tube 3 preferably formed from wrought iron or steel pipe threaded at both ends. The lower end of the anchoring tube 3 is screwed onto the internally threaded hub of a flanged anchoring plate 4, and the upper end of said anchoring tube 3 is screwed into 30 a coupling sleeve 5, the upper end of which is preferably set flush with the surface of the pavement y .

The signal post comprises a casing or rigid portion indicated as an entirety by the numeral 6, and a yielding resilient tube 7 preferably of fabric and rubber composition. This base proper may take various forms but will preferably be of the type disclosed and claimed in our prior application, above 45 identified.

The numeral 8 indicates a tubular coupling or sleeve that is telescoped onto the lower end of the flexible tube 7 and is yieldingly attached thereto preferably by nut-equipped

bolts 9 and an external clamping ring 10. 50 This tubular coupling 8 has a downwardly projecting threaded portion that is adapted to be screwed onto the coupling sleeve 5, as best shown in Fig. 2. The numeral 11 indicates a wire-containing cable that is extended 55 from a suitable point through the concrete pavement or road bed, is passed through a perforation in one side of the anchoring tube 8 and thence upward through the interior of the post for the purpose of controlling signals or supplying light bulbs with current.

When this anchoring device is imbedded in the concrete, its elements 3, 4 and 5 will be securely held together and against rotation and solidly supported against vibratory 60 movements of all kinds, so that it will therefore afford a very firm and efficient anchor. This anchoring device is of very simple construction, may be made at small cost, its parts quickly assembled and, when applied, will 65 not get out of adjustment nor break down. Moreover, it is vertically adjustable, so that the flanged base plate 4 may be set at different depths within the concrete. The coupling sleeve 5 should be set flush with the 70 top of the road bed, and when the post is not applied, it should be closed with a suitable plug, so that it will not form an obstruction in the road. Obviously, the post may be very 75 quickly applied to the anchoring base or 80 quickly removed therefrom simply by screwing the coupling tube 8 into and out of the anchored sleeve 5.

What we claim is:

A traffic signal comprising an anchoring 85 tube adapted to be secured in the road bed, a post-supporting coupling detachably secured to the upper end of said anchoring tube and having a rounded and contracted upper end portion projecting above the road bed, and 90 a signal post having a flexible lower end portion telescoped over the rounded portion of said coupling and rigidly secured thereto below said rounded portion.

In testimony whereof we affix our signatures.

JOHN RANK.
HENRY W. RANK.
